UNITED STATES PATENT OFFICE.

LOUIS JAENICHEN, OF DETROIT, MICHIGAN, ASSIGNOR TO THE STANDARD COMPUTING SCALE COMPANY, OF DETROIT, MICHIGAN, A CORPORATION.

DESIGN FOR A SCALE-FRAME.

No. 40,157.

Specification for Design.

Patented July 20, 1909.

Application filed April 30, 1908. Serial No. 430,236. Term of patent 14 years.

To all whom it may concern:

Be it known that I, LOUIS JAENICHEN, a citizen of the United States, residing at Detroit, in the county of Wayne and State of Michigan, have invented a new, original, and ornamental Design for Scale - Frames, of which the following is a specification, reference being had to the accompanying drawing, forming part thereof.

The figure is a perspective view of a scale frame, showing my new design.

I claim:

The ornamental design for a scale frame as shown.

LOUIS JAENICHEN.
